MEANS AND METHOD FOR CONTROLLING
OUTPUT FROM CRYSTAL MICROPHONES

Francis M. Schmidt, North Tonawanda, N. Y., assignor to The Rudolph Wurlitzer Company, North Tonawanda, N. Y., a corporation of Ohio

Application July 15, 1939, Serial No. 284,689

3 Claims. (CL 179—1)

This invention relates to certain new and useful improvements in the means and method for controlling the output from a crystal microphone.

It has for its chief object to provide a novel system for controlling the output from a crystal microphone at the microphone, irrespective of the remoteness of the associated electro-acoustical system from the microphone.

Another object of the invention is to provide a microphone control of this character which is so designed as to effectually and faithfully control the volume of the microphone without the occurrence of frequency discrimination, and which control provides for a uniform volume level whether the electro-acoustical system be located near or at a remote distance from the microphone.

Other features of the invention reside in the construction and arrangement of parts herein-after described and particularly pointed out in the appended claims.

In the accompanying drawing:

Figure 1 is a side elevation of the improved microphone control associated diagrammatically with an amplifier and speaker system. Figure 2 is a diagrammatic view of the circuit embodying my invention.

Similar characters of reference indicate corresponding parts throughout the several views.

Heretofore, when it has been desired to operate a crystal microphone and to have the volume of the crystal microphone and its associated electro-acoustical system controllable from a point near to or within reach of the microphone when such associated governing equipment has been located at a point remote from the microphone, it has been necessary to use a variable condenser as a volume control unit because of the capacitative nature of a crystal microphone unit. Such variable condenser controls, however, are bulky and expensive, and it is therefore desirable to create a new method for controlling the volume of the crystal microphone directly at the microphone.

In this connection, if a resistive control were to be used the frequency characteristic would change with the volume control and the response would not be suitable nor faithful. If an electrical network were used to correct for this frequency discrimination, it would be expensive and suitable only as long as the connecting cable between the crystal microphone and the remotely associated acoustical system was not lengthened nor shortened, in which case frequency discrimination would exist.

Referring now to the drawing, wherein my invention has been illustrated, by way of example, in association with an electro-acoustical system, the numeral 10 indicates the crystal microphone mounted on a suitable standard 11, and 12 indicates generally the reproducing apparatus or amplifier which is located remotely from the microphone and which is provided with a suitable loud speaker unit 13 of well known construction. Connecting the reproducing apparatus with the microphone is a cable 14 which may be of any length and which contains the wires of the control circuit. Associated with and applied to the microphone is a switch 15 and a volume control knob 16, whereby the user can readily control, directly at the microphone, the switching of the microphone "on" and "off" as well as govern its volume output.

The crystal microphone 10 is connected by the wire 17 with the control grid 18 of a variable, mutual conductance amplifier or electron tube 19 constituting a part of the amplifier system 12. The amplification of this tube is varied by changing its bias voltage by means of the volume control knob 16 which is operatively connected to a variable resistor 20 of any well known type, that shown in the drawing including the resistors 21, and adjustable control element 22 to which the knob 16 is connected. Leading from the adjustable control element 22 of the resistor 20 is a wire 23 which is connected through filter elements 24, 25 and 26 to the cathode 27 of the electron tube. The function of these filter elements is to eliminate electrical noise as the volume control is varied and to stabilize the amplifier circuit to prevent degeneration therein.

The variable resistor 21 is so connected that a constant or fixed voltage is maintained at all times, and to this end one terminal thereof is connected by a wire 28 through the cable 14 to a resistor 29 and thence to the supply voltage or battery 30 of the amplifier unit 12. The return circuit from this supply voltage is carried through the cable 14 by a wire 31 connected to the other terminal of the variable resistor element 21. When the adjustable control element 22 of the resistor is changed by means of the control knob 16 the bias of the tube 19 is altered thus changing the amplification of the tube and the frequency characteristic of the amplification circuit follows that of the crystal microphone for all volume levels. The cable 14 between the microphone and the associated amplifier system may vary in length and no frequency discrimination occurs.

The amplifier system 12 which is located remotely from the microphone and connected thereto is of a conventional type having audio amplifier or electron tubes 32, 33, 34 and 35 connected to the speaker 13.

I claim as my invention:

1. In combination, a crystal microphone, an electro-acoustical system associated therewith for operative connection thereto, an amplifying circuit for the microphone operatively connected to said electro-acoustical system and including a variable, mutual conductance electron tube having its control grid connected to said microphone, a variable resistance associated with said amplifying circuit and connected to the cathode of said tube for varying the amplification thereof, and means located adjacent the microphone for controlling said variable resistance.

2. The combination with a crystal microphone and an associated electro-acoustical system located remotely therefrom, of a circuit operatively

connected to said electro-acoustical system and including a variable, mutual conductance electron tube having its grid connected to said microphone and its output circuit coupled to said acoustical system, and a variable resistance operatively connected to the cathode of said tube for varying its amplification and having a control element therefor positioned adjacent to said microphone.

3. The combination with a crystal microphone and an associated electro-acoustical system located remotely therefrom, of a circuit including a variable, mutual conductance electron tube constituting a part of the electro-acoustical system and having its control grid connected to the microphone, and a variable resistance connected to the cathode of said tube and having a control element therefor for varying the amplification of such tube by changing its bias voltage.
